SPRAY GUN FOR LIQUID COATING MATERIALS

Carl A. Sundberg, Bloomfield Hills, Mich., assignor to
The DeVilbiss Company, Toledo, Ohio, a corporation
of Ohio

Filed Mar. 13, 1964, Ser. No. 78,987

Term of patent 14 years

(Cl. D62—2)

FIG. 1 is a top plan view of a spray gun for liquid coating materials embodying my new design;

FIG. 2 is a side elevational view thereof;

FIG. 3 is a rear elevational view thereof;

FIG. 4 is a front elevational view thereof; and

FIG. 5 is a bottom plan view.

The dominant features of the design reside in the portions shown in full lines.

I claim:

The ornamental design for a spray gun for liquid coating materials, substantially as shown and described.
